DESIGN FOR A STRIP OF ARTIFICIAL LEAVES

Wilhelm Hoffmeister, Neustadt, Germany

Application February 3, 1936, Serial No. 61,054
In Germany July 10, 1935

Term of patent 3½ years

To all whom it may concern:

Be it known that I, Wilhelm Hoffmeister, a citizen of the German State, residing at No. 29, Bahnhofstrasse, Neustadt, Germany, have invented a new, original, and ornamental Design for a Strip of Artificial Leaves, of which the following is a specification, reference being had to the accompanying drawing, forming part thereof.

The figure is an elevational view of a strip of artificial leaves showing my new design. The leaves united to form the strip are of different length, the longest leaves at the middle and shorter leaves at the ends, the strip being of no appreciable thickness and the back being plain or bearing ornamentation embodying the motif shown on the front thereof.

I claim:—

The ornamental design for a strip of artificial leaves, substantially as shown and described.

WILHELM HOFFMEISTER.
